UNITED STATES PATENT OFFICE.

WILLIAM A. BARR, OF WASHINGTON, DISTRICT OF COLUMBIA.

MAIL-BOX.

SPECIFICATION forming part of Letters Patent No. 673,152, dated April 30, 1901.

Application filed January 29, 1901. Serial No. 45,223. (No model.)

To all whom it may concern:

Be it known that I, WILLIAM A. BARR, a citizen of the United States, residing at Washington, District of Columbia, have invented 5 certain new and useful Improvements in Mail-Boxes; and I do declare the following to be a full, clear, and exact description of the invention, such as will enable others skilled in the art to which it appertains to make and use 10 the same, reference being had to the accompanying drawings, and to the letters of reference marked thereon, which form a part of this specification.

This invention relates to improvements in 15 mail-boxes, and has for one object the production of a false bottom which is adapted to be applied to existing as well as new boxes and which serves to preserve the mail-matter in a dry condition and greatly facilitates collections. 20

Another object of my invention is the production of an improved door designed more especially for use in connection with what are known as "rural" mail-boxes, and a further object is the provision of improved signaling means for the patron and carrier. 25

The nature of my invention will be understood from a reading of the following description, taken in connection with the accompanying drawings, in which— 30

Figure 1 is a perspective view of a mail-box embodying my invention. Fig. 2 is a longitudinal sectional view of the same, and Fig. 3 is a perspective view of the false bottom.

Referring to the drawings by letter, A denotes the box, having an opening in its front end, and B is the door, which is hinged at its lower side to swing downwardly and which at its upper side is bent inwardly to form a 35 projection b, in which is a hole to receive the bolt of a lock c.

b' designates a flange at the upper side of the door, having a depending portion b², serving as a handhold. The box is provided at 40 the upper side of the opening with a flange a of a width to extend beyond the door-flange b' to prevent the entrance of rain and snow, the flange a being transversely curved on a

radius of which the pintle of the door-hinge is the center. 50

D denotes a false bottom, preferably constructed from sheet metal and consisting of a corrugated or fluted plate supported by legs d, preferably at an incline to direct the mail-matter to the front of the box. The 55 ribs or projections d' d' formed by the corrugations support the mail-matter above the depressions d² d², and not only is the matter thereby held out of contact with any water which may have entered the box, but the 60 withdrawal thereof is greatly facilitated by reason of the inclination of the false bottom and the ease of handling, the depressions being of sufficient depth to allow of the ready insertion of the fingers beneath the letters 65 and other contents. The rear end of the false bottom is preferably curved upwardly, and the front end is elevated slightly above the bottom of the box. In each depression are holes d³ d³ for the escape of water, and a' 70 a' are holes in the box-bottom for a similar purpose. The box may be mounted to have a slight inclination to direct the water to any desired point of escape.

E' denote signal-arms, commonly pivoted in a pin or bolt e at the side of the box. These arms are differently colored, and either one is inserted to a position above the top of the box to indicate that there is mail to be collected or that there is mail to be delivered. 75

I claim as my invention—

1. As a new article of manufacture, a false bottom for mail-boxes consisting of a plate having an area equal to the horizontal area of the box and adapted to be supported by 85 the bottom of the box, said plate having mail-matter-supporting ribs extending in the direction of the collection-opening the ribs being spaced apart sufficiently to permit insertion of the hand beneath the mail-matter. 90

2. As a new article of manufacture, a false bottom for mail-boxes consisting of a perforated sheet-metal plate having an area equal to the horizontal area of the box and adapted to be supported at an inclination by the 95 bottom of the box, said plate having mail-

matter-supporting ribs extending in the direction of the collection-opening the ribs being spaced apart sufficiently to permit insertion of the hand beneath the mail-matter.

5 3. A mail-box having a transversely-curved flange above the door-opening, and a door for the opening having an inner flange perforated to receive the locking-bolt and having

an outer flange of less width than the box-flange.

In testimony whereof I affix my signature in presence of two witnesses.

WILLIAM A. BARR.
